UNITED STATES PATENT OFFICE

172,749

LAMP

Ernest L. Howard, Daly City, Calif.

Application March 5, 1954, Serial No. 29,368

Term of patent 7 years

(Cl. D48—20)

To all whom it may concern:

Be it known that I, Ernest L. Howard, a citizen of the United States of America, residing at Daly City, in the county of San Mateo and State of California, have invented a new, original, and ornamental Design for a Lamp, of which the following is a specification, reference being had to the accompanying drawing, forming a part thereof.

The figure is a perspective view of a lamp, showing my new design.

I claim:

The ornamental design for a lamp, substantially as shown.
